UNITED STATES PATENT OFFICE.

JEAN G. THEOBALD, OF NORTH ATTLEBOROUGH, MASSACHUSETTS, AS-
SIGNOR TO THE FRANK M. WHITING & COMPANY, OF SAME PLACE.

DESIGN FOR A MOUNT FOR DISHES.

SPECIFICATION forming part of Design No. 29,325, dated September 13, 1898.

Application filed August 15, 1898. Serial No. 688,636. Term of patent 3½ years.

To all whom it may concern:

Be it known that I, JEAN G. THEOBALD, a citizen of the United States, residing at North Attleborough, in the county of Bristol, State of Massachusetts, have invented and produced a new and original Design for a Mount for a Dish or Similar Article, of which the following is a specification, reference being had to the accompanying drawing, forming part thereof.

The figure shows the face of my design, the obverse thereof being plain.

As shown in the drawing, the leading feature of my design consists in a center cluster of husks flanked on either side by series of scrolls with leaf ornamentation.

More particularly described, my design is as follows: The central ornamentation A is a cluster of husks, of which 1 is the largest, with 20 a tripetal formation, and 2 a similar ornament with petals embracing a bud 3. The arms, of which bands B' are the head members, extend from either side of cluster A, similarly disposed to their common axial line. Both

bands B' are similar in outline. They may be 25 described as double foliated scrolls with oppositely-disposed heads formed by folded conventionalized leaves, the inner heads 4 4 being larger than the outer, 5 5. From the minor members 6 6 of the double scrolls extend 30 branches of conventionally-treated leaves 7 7, which sweep across and partially obscure the plain surface 8 8. The arm terminations C and C' are C-shaped double scrolls oppositely disposed in relation to their common 35 axial line and similar, except that two minor heads 10 10 are introduced into the inner face of scroll C'. The scroll terminations 9 9 are similar in general outline to heads 5 5.

Having described my invention, what I claim as new, and desire to secure by Letters Patent, is—

The design for a mount for a dish or similar article as herein shown and described.

JEAN G. THEOBALD.
